(57) **CLAIM**

The ornamental design for a dispensing instrument, as shown and described.

DESCRIPTION

FIG. 1 is a perspective view of the dispensing instrument showing my new design, as seen from the front, above and right side;

FIG. 2 is a rear perspective view thereof;

FIG. 3 is a front elevation thereof;

FIG. 4 is a rear elevation thereof;

FIG. 5 is a side elevation thereof with the other side elevation view being identical thereto,

FIG. 6 is a top plan view thereof; and,

FIG. 7 is a bottom plan view thereof.
